UNITED STATES PATENT OFFICE

CARL J. LINDEGREN, OF PROVIDENCE, RHODE ISLAND, ASSIGNOR TO CROMPTON & KNOWLES LOOM WORKS, OF WORCESTER, MASSACHUSETTS, A CORPORATION OF MASSACHUSETTS

BOX MOVING MECHANISM FOR LOOMS

Application filed June 3, 1931. Serial No. 541,855.

This invention relates to drop box looms and more particularly to the box moving mechanism. In the operation of such looms, a shuttle may become displaced or the vertical shifting of the boxes may be otherwise interfered with. It is accordingly desirable to provide a yielding or give-way connection which will permit the box lifting mechanism to be rendered inoperative in such an event, without causing breakage of any parts of the mechanism. It is also desirable that the yielding or give-way connection be capable of easy and accurate re-setting.

It is the general object of my invention to provide a box moving mechanism having an improved yielding or give-way connection embodied in its construction.

My invention further relates to arrangements and combinations of parts which will be hereinafter described and more particularly set forth in the appended claims.

A preferred form of the invention is shown in the drawings, in which

Fig. 1 is a side elevation of a loom having my invention embodied therein;

Fig. 2 is an enlarged side elevation of the box moving mechanism;

Fig. 3 is a plan view of the mechanism shown in Fig. 2;

Fig. 4 is a detail sectional plan view, taken along the line 4-4 in Fig. 2;

Fig. 5 is a detail sectional view, taken along the line 5-5 in Fig. 2, and

Fig. 6 is an enlarged front elevation of certain parts.

Referring to the drawings, I have shown portions of a loom, including a loom side 10 and drop boxes 11 mounted on a lay 12 and vertically positioned by the usual lifter rod 13. The rod 13 is pivotally connected at 14 to the lower end of a link 15, by which the lifter rod 13 is connected to a lifter lever 16. The lever 16 rocks upon a floating pivot stud 17 and is provided with the usual counter-weight 18. The pivot stud 17 of the lever 16 is mounted at an intermediate point in a lever 20, pivoted at 21 to a bracket 22 on the loom side 10.

The lifter lever 16 is connected at its rear end by a link 24 to a crank-pin 25 (Fig. 2)

mounted in the rear side of a cam 26, secured to one end of a back pinion shaft 27 (Fig. 3). The lever 20 is similarly connected by a link 30 to a crank-pin 31, secured in the rear face of a cam 32 fixed at one end of a front pinion shaft 33.

The shafts 27 and 33 are rotatable in fixed bearings 35 and 36 (Fig. 3) and are provided with mutilated pinions 37 and 38 fixed to said shafts. A two-part intermittent driving gear 40 is loosely mounted on the usual cam or bottom shaft 41 of the loom.

The pinions 37 and 38 are provided with sliding teeth 42 and 43 (Fig. 3) mounted on arms 44 and 45 which project axially toward the pinions from grooved collars 46 and 47. These collars 46 and 47 are slidable on the pinion shafts 27 and 33 and are positioned by yoke members 48 and 49, fixed on plungers 50 slidable in fixed bearings 51 and yieldingly pressed outward by springs 52 (Fig. 3). The plungers 50 are moved in the opposite direction by cords or cables 53, connected to suitable pattern-controlled actuating mechanism.

When one of the plungers 50 is moved inward by one of the cords 53, the corresponding sliding tooth 42 or 43 is thereby moved to inoperative position. When the plungers are moved outward by the springs 52, the teeth are correspondingly moved to operative position, thus enabling the driving gear 40 to partially rotate the corresponding pinion 37 or 38.

Locking plates 55 (Fig. 2) cooperate with hub portions of the gear 40 to hold the pinion shafts 27 and 33 in predetermined positions, before and after actuation by the driving gear 40.

A driving collar 60 (Fig. 4) is mounted on the outer end of the cam shaft 41 of the loom, in a position adjacent to the driving gear 40, which, as previously stated, is loose on the cam shaft 41. The collar 60 is firmly secured to the shaft 41 in any convenient manner as by a locking member 62 (Fig. 6) concaved to provide spaced engaging edge portions 63. This locking member 62 is mounted in a slot or key-way 64 of the collar 60 and may be forced against the side of the shaft 41 by a set-screw 65.

This type of locking member has been found very effective and convenient as a means for attaching the collar 60 to the shaft 41, as the collar is held firmly, both axially and angularly, by the locking member 62, and no spot or key-way on the shaft 41 is required.

A plunger 70 (Fig. 4) is mounted in a recess 71 in the collar 60, in a position parallel to the axis of the shaft 41. A spring 72 in the recess 71 forces the plunger 70 yieldingly outward toward the driving gear 40, and such outward movement is limited by a nut 73, threaded on the shank of the plunger 70.

The outer end of the plunger 70 is of conical shape, with the sides of the cone preferably forming an angle of substantially 60°. A recess or opening 80 is provided in the end face of the gear 40 to receive the conical end of the plunger 70, this opening also being preferably conical and of a corresponding angle.

By suitably selecting the angle of the conical portion of the plunger and by providing a spring 72 of suitable strength, the gear 40 is effectually rotated by the driving shaft 41 through this give-way connection, but the parts will yield before breakage if movement of the drop boxes or any part of the box-moving mechanism is prevented.

The parts are easily re-set by rotating the cam shaft 41 until the plunger 70 returns to its recess 80. As only one recess 80 is provided in the face of the gear 40, and as the cam shaft 41 makes only one revolution for two movements of the lay 12, the parts are always in predetermined relation when the yielding connection is restored.

The give-way connection thus provided is formed of few and relatively inexpensive parts and is particularly desirable on account of the very small space required for its installation and use.

Having thus described my invention and the advantages thereof, I do not wish to be limited to the details herein disclosed, otherwise than as set forth in the claims, but what I claim is:—

1. In a loom having vertically shifting drop boxes and a lifter rod and lifter lever associated therewith, a box moving mechanism comprising links connected to move and position said lifter lever, crank arms for said links, pinion shafts for said arms, mutilated pinions on said pinion shafts, an intermittent driving gear, means to selectively engage said pinions with said driving gear, a driving shaft on which said driving gear is loosely mounted, a collar fixed to said shaft adjacent said driving gear, a plunger mounted in said collar and yieldingly movable toward the face of said gear in a line parallel to the axis of said shaft, and a spring for said plunger, the outer end of said plunger being conical and seating in a recess in the adjacent

end face of said driving gear, thereby forming a give-way connection between said driving shaft and driving gear.

2. In a loom having vertically shifting drop boxes and a lifter rod and lifter lever associated therewith, a box-moving mechanism comprising links connected to move and position said lifter lever, crank arms for said links, pinion shafts for said arms, mutilated pinions on said pinion shafts, an intermittent driving gear, means to selectively engage said pinions with said driving gear, a driving shaft on which said driving gear is loosely mounted, a collar fixed to said shaft adjacent said driving gear, a plunger mounted in said collar and yieldingly movable toward the face of said gear in a line parallel to the axis of said shaft, and a spring for said plunger, the outer end of said plunger being conical at an angle of substantially 60° and seating in a conical recess of similar angle in the adjacent end face of said driving gear, thereby forming a give-way connection between said driving shaft and driving gear.

In testimony whereof I have hereunto af- fixed my signature.

CARL J. LINDEGREN.
